[57] CLAIM

The ornamental design for relief valve, substantially as shown and described.

DESCRIPTION

FIG. 1 is a front elevational view of a relief valve showing my new design;

FIG. 2 is a right side elevational view thereof;

FIG. 3 is a rear elevational view thereof;

FIG. 4 is a top plan view thereof, the bottom being a mirror image of the top shown;

FIG. 5 is a cross sectional view taken along line V—V of FIG. 3; and

FIG. 6 is a left side elevational view thereof.

FIG. 1

FIG. 2

FIG. 3

FIG. 4

FIG. 5

FIG. 6
